UNITED STATES PATENT OFFICE.

JOHN S. GOLDBERG, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,086,594

Specification of Letters Patent. Patented Feb. 10, 1914.

Application filed November 2, 1906. Serial No. 341,735.

To all whom it may concern:

Be it known that I, JOHN S. GOLDBERG, a citizen of the United States, residing at Chicago, in the county of Cook and State of Illinois, have invented a certain new and useful Improvement in Carbureters, of which the following is a full, clear, concise, and exact description, reference being had to the accompanying drawings, forming a 10 part of this specification.

My invention relates to carbureters, particularly to carbureters for use on gasolene or other hydro-carbon oil engines.

The carbureter of my invention comprises 15 improved features of construction and arrangement and improved features of automatic adjustment which enable regulation of the gas flow with a minimum number of operations, there being only one lever whose 20 operation serves to control the mixture and feeding of gas to the engine.

In the accompanying drawings which illustrate my invention, Figure 1 shows a top view of the carbureter, various parts 25 having been removed in order to show the valve seat and the seat for the float; Fig. 2 is a sectional view taken on line 2—2 of Fig. 1, the parts removed in Fig. 1 being shown in position; Fig. 3 is a sectional view 30 taken on line 3—3 of Fig. 1; Fig. 4 is a sectional view taken on line 4—4 of Fig. 1, and Fig. 5 is a top view, showing the valve in position on the valve seat.

The frame 1 supports at one end the spindle valve seat 2 and at the other end the cylindrical frame 3. Extending upwardly from the valve seat 2 is the hollow cylindrical standard 4 through which extends the valve rod 5, having at its lower end a reduced extension 6 terminating in the valve point 7 for controlling the inlet 8. Through the walls of the standard 4 just above the base 2 are the diametrically opposite openings 9 and 10 in which are pivoted on pivots 11 and 12 the levers 13 and 14. The inner ends or points 15 and 16 of these levers respectively engage the shoulder 17 of the valve rod while the outer arms 17' and 18 of the levers engage the float cylinder 19 which float is hollow and which has a central opening 20 through which passes the standard 4. Extending upwardly from the frame 1 and surrounding the valve seat part 2 is the angular projection 21 within which 55 is disposed the lower end of cylinder 22

which is preferably of glass or other transparent material. A cap 23 fits the upper end of the cylinder 22 and has a central threaded opening 24 for engaging the threads 25 at the upper end of the standard 4. A guide nut 26 is also adapted to engage the threads at the end of the standard and has the guide 27 through which passes the upper end 28 of the valve rod. Washers or gaskets 29 and 30 being placed in position, as shown, and the cap 23 and lock nut 26 screwed into place, a sealed chamber is provided. By means of suitable fittings 31, the valve chamber 32 may be connected through pipe 33 with a source of oil supply, such as gasolene. When the float reservoir is empty, the weight of the float will be sufficient to turn the levers 13 and 14 to raise their inner ends and consequently to raise the valve rod to hold the spindle valve pin 75 up to open the inlet 8 to allow entrance of oil into the reservoir. However, as the oil rises in the reservoir, the weight of the float will be gradually lifted from the levers, and when the oil reaches a certain fixed level, the weight of the valve rod will overcome the weight of the float and will drop to close the inlet 8. With this arrangement the oil in the reservoir is automatically maintained at a constant fixed level. By 85 means of a cock 34 suitably connected with the fittings 31, the reservoir may at any time be drained.

Within the cylindrical frame 3 is the cylindrical valve seat frame 35. The interior 90 36 of this valve frame is connected with the air inlet 37, while the channel or outlet 38 through the body of the valve seat frame connects through passageway 39 with the reservoir, as best shown in Figs. 1, 2 and 3, 95 the passageway 39 leading through the supporting frame 1. The space surrounding the valve seat frame constitutes a carbureting chamber 40 which may be connected through outlet 41 with the engine in any 100 suitable manner. The valve block 42 is mounted on top of the valve seat, as shown in Figs. 2, 3 and 5, and a guide stem 43 extends downwardly from this valve into the guide pedestal 44. Extending upwardly in 105 the chamber 36 through said valve block is the horizontal passageway 45 for receiving crank pin 46, extending from the crank cylinder 47, journaled in the bearing frame 48 extending laterally from the frame 3, as 110

best shown in Figs. 1 and 2, the crank cylinder supporting at its end the adjusting arm 49. Upon oscillation of the arm 49 the crank pin 48 will cause vertical reciprocation of the valve block. In the top of the valve block is a cylindrical pocket 50 for receiving a worm wheel 51 whose supporting stem 52 at one end is journaled in the pocket 53 and whose upper end extends through an opening or guideway 54 through cap 55 and nut extension 56, this cap 55 having a threaded flange 57 for engaging the threaded upper end of the frame 3, the nut part 56 being integral with the cap part. The worm wheel is confined in the pocket 50 by the plate 58 held to the valve block by the screw 59, the valve stem 52 passing through the opening 60 in this plate. Extending through the valve block and through the edge of the pocket 50 is the channel 61 which registers with the outlet 38 which communicates through the channel 39 with the reservoir. Extending through this channel 61 and into outlet 38 is a valve rod 62. At the upper end of this valve rod is a groove 63 whose rear face has the teeth 64 engaged by the worm wheel so that rotation of the worm wheel will cause vertical movement of the valve rod. The lower end 65 of the valve rod is cut away at a gradual bevel, as best shown in Fig. 3, and thus as the valve rod is raised or lowered, the area of the end of the outlet 38 is increased or decreased correspondingly. The vertical movement of the valve rod is limited by the upper and lower walls of the groove 63.

The level of the oil in the outlet passage-way 38 will be the same as that in the reservoir, and when the engine is to be started, the arm or lever 49 is turned a suitable distance, thereby raising the valve block to open communication through the chamber 36 and between the inlet 37 and the carbureting chamber 40 and also to raise the valve rod 62 to establish communication between the outlet channel 38 and the carbureting chamber. When the engine is started, the suction draws in air through the pipe 37 which air rushes through between the valve block and top of the valve seat past the end of the outlet 38, thus sucking up the gasoline from the passageway 38 which gasoline is thoroughly vaporized and mixed with the air in the carbureting chamber before passing to the engine. The desired proportion between air and gasoline is as adjusted by turning the stem 52 which may be done by means of a wrench engaging the polygonal end 66 of the shaft 52 supporting the worm wheel, and this proportion of gasoline and air will be maintained during any adjusting movement of the arm 49. This proportion of adjustment could, of course, be accomplished in the first place by giving the

proper taper to the end 65 of the valve rod 62, but this would require exact and expensive workmanship and besides might very easily lose its adjustment. By the use of the worm wheel adjusting arrangement, just 70 the ordinary care need be taken in beveling the end 65, the fine adjustment being accomplished by the worm wheel arrangement.

Instead of employing set screws to hold the crank shaft 47 in its bearings, I cause 75 the flange 57 to perform this function, this flange extending into an annular groove 67 surrounding the inner end of the crank shaft 47.

It will be noticed that the construction 80 and arrangement of my device are very simple, it requiring very little work to get at any of the parts, both for inspection or repairs. For example, if the spindle valve in the reservoir is desired to be inspected, 85 it is necessary only to unscrew the cap nut 26 whereupon the valve rod may be withdrawn. If it is desired to examine the float, the cap nut 26 and cap 30 are removed whereupon the float can be lifted from the 90 standard 4; also by removing the cap 55 from the frame 3, the crank mechanism may be immediately withdrawn and the valve block with all its attachments lifted from the seat, and this simple arrangement is a 95 very desirable feature. The reservoir cylinder 22 being of glass enables ready determination of the level of oil or the position of the float in the reservoir. I do not wish to be limited, however, to the exact arrangement and construction shown and described, 100 as changes may be readily made without departing from the scope of my invention.

I claim as new and desire to secure by Letters Patent: 105

1. In a carbureter, the combination with a carbureting chamber, an inlet for air into said chamber and an inlet passageway for fuel terminating in said chamber, a valve stem engaging in said passageway, a member in which said valve stem is mounted, an adjusting rod extending from said member and rotatably pivoted therein, and means adapted upon the turning of said adjusting rod to cause longitudinal non-rotative movement of the valve stem and thereby adjustment of the inlet passageway. 110

2. In a carbureter, the combination with a carbureting chamber, an inlet for air into said chamber and an inlet passageway for fuel terminating in said chamber, a valve stem engaging in said passageway, a member in which said valve stem is mounted, an adjusting rod extending from said member and rotatably pivoted therein, a worm wheel on said adjusting rod, and threads on said valve stem engaging with said worm wheel whereby rotation of the adjusting rod will cause adjustment of the valve stem with reference to the inlet passageway. 115 120 125 130

3. In a carbureter, the combination of a casing forming a carbureting chamber, an inlet to said chamber for air, an inlet passageway to said chamber for fuel, a valve stem engaging in said passageway, an adjusting rod in said casing and parallel to the valve stem, worm threads carried by said rod, and teeth or threads on the valve stem engaging said worm threads, whereby rotation of the adjustment rod will cause movement of the valve stem in a direction parallel to the adjusting rod.
4. In a carbureter, the combination of a

carbureting chamber, a fuel passageway, an air passage, a valve stem engaging in said fuel passage, an adjusting member having worm threads thereon, and a rack on said valve stem for coöperating with said worm threads.

In witness whereof, I hereunto subscribe 20 my name this 29th day of Oct. A. D., 1906.

JOHN S. GOLDBERG.
